UNITED STATES PATENT OFFICE.

GEORGE BEARHOPE, OF COLUMBUS, INDIANA, ASSIGNOR OF ONE-THIRD TO WILLIAM A. MOONEY AND ONE-THIRD TO THOMAS MOONEY, BOTH OF COLUMBUS, INDIANA.

PROCESS OF STUFFING LEATHER AND APPARATUS THEREFOR.

No. 874,882.

Specification of Letters Patent.

Patented Dec. 24, 1907.

Application filed July 14, 1905. Serial No. 269,718.

To all whom it may concern:

Be it known that I, GEORGE BEARHOPE, a citizen of the United States, residing at Columbus, in the county of Bartholomew 5 and State of Indiana, have invented certain new and useful Improvements in Processes of Stuffing Leather and Apparatus Therefor, of which the following is a specification.

At a certain stage in the manufacture of 10 certain varieties of leather it is subjected to a process known as "stuffing". That is, it is impregnated with some one of a variety of preparations, of which grease or tallow is a leading ingredient. Some of the best of 15 these preparations are quite hard, and only melt to the consistency best adapted for application to the leather when subjected to a comparatively high degree of heat. In the processes commonly used it has been difficult to utilize the degree of heat necessary to 20 the best results so far as the stuffing preparation is concerned without endangering the quality of the leather, as heat has a tendency to destroy the strength of the fibers when in 25 the ordinary condition at which the stuffing has heretofore been performed. In other words, there has been a constant contest between securing efficiency of stuffing conditions and the danger of impairing the 30 strength of the leather by heat while doing the work.

I have discovered that by carefully evaporating all the moisture from the leather when it has reached the stage for stuffing I am enabled to utilize a materially higher degree of 35 heat than has heretofore been found to be safe; and by my improved apparatus and process (as will be hereinafter described) I am able to apply the stuffing preparation or 40 mixture also at a much higher degree of heat, so that it will thoroughly permeate the leather with the result that I have a much evener and better product. With the stuffing preparation heated to the desired degree, and thus 45 reduced to the proper consistency, I am also able to exercise a considerable economy in its use. That is, it takes a less quantity to accomplish the desired result than has heretofore been employed, and there is less waste. 50 The accompanying drawing is a diagrammatic perspective view illustrating (in a conventional way) the apparatus which I employ in carrying out my invention.

I first take the leather after it has been 55 subjected to the proper preparatory treat-

ment and suspend it in a drying chamber. Here I subject it to the action of heat until all moisture is thoroughly evaporated, so the leather is completely dried. When thoroughly dry, the leather will without injury 60 endure a considerably higher degree of heat than it will when moist. I prepare the stuffing mixture by first melting it in a suitable tank, as 21. I then convey it into a compression tank, as 22. To said compression tank I connect an air compressor, as 23, so as to secure the necessary amount of pressure therein. To this compression tank I secure a suitable hose, as 24, having a spray nozzle, as 25. I then provide a suitable 65 table, the surface 26 of which is preferably formed of coarse wire cloth, on which to lay the dried and heated leather. I now take the leather from the chamber in which it has been heated and the moisture evaporated 70 therefrom, and while still dry and hot place it upon the table. I then apply the stuffing mixture thereto through the spray nozzle. The leather and the mixture both being hot, the latter will penetrate the former readily, 75 and I, therefore, spray said mixture against the leather on one side until it appears on the other, so that the fibers thereof are thoroughly permeated with said mixture. In its heated liquid condition, any surplus stuffing 80 mixture will run off down through the reticulated table top, and be caught by a suitable drip tank, as 27, beneath, from whence it can be run off to any suitable receptacle and thence taken back to the melting tank 85 and reused. After the leather has been thus treated it should be immersed in cold water and allowed to remain about one day, when it will be found to be soft and pliable, and of an excellent quality. The subsequent treatment 90 should be the same as that to which leather is usually subjected in finishing.

Having thus fully described my said invention, what I claim as new and desire to secure by Letters Patent, is,—

1. An apparatus for stuffing leather consisting of a melting tank, a compression tank, means whereby pressure is generated within said tank, a hose connected to said tank, a spray nozzle on said hose, and a perforated 105 topped table on which to place the hides while the mixture is being applied from said nozzle.

2. An apparatus for stuffing leather consisting of a melting tank, a compression tank, 110

means whereby pressure is generated within said tank, a hose connected to said tank, a nozzle on said hose, and a suitable table on which to place the hides while the mixture is being applied from said nozzle.

In witness whereof, I have hereunto set my hand and seal at Indianapolis, Indiana,

this tenth day of July, A. D. one thousand nine hundred and five.

GEORGE BEARHOPE. [L. S.]
